UNITED STATES PATENT OFFICE.

WILLIAM A. EDWARDS, OF CHICAGO, ILLINOIS, ASSIGNOR TO FINDEISEN & KROPP MFG. CO., OF CHICAGO, ILLINOIS, A CORPORATION OF ILLINOIS.

CARBURETER.

1,335,430.

Specification of Letters Patent. Patented Mar. 30, 1920.

Application filed May 14, 1914. Serial No. 838,425.

To all whom it may concern:

Be it known that I, WILLIAM A. EDWARDS, a subject of the King of Great Britain, and a resident of the city of Chicago, in the county of Cook and State of Illinois, have invented certain new and useful Improvements in Carbureters; and I do hereby declare that the following is a full, clear, and exact description of the same, reference being had to the accompanying drawings, and to the numerals of reference marked thereon, which form a part of this specification.

The ability of a gasolene engine or other hydro-carbon motor to respond instantly to an adjustment of the throttle by an operator is very seldom dependent upon the particular construction of the engine itself, but is rather a feature depending upon the capability of the carbureter for introducing fuel to the engine in the proper proportion and amount, simultaneously with a movement of the throttle valve. In a great many cases a motor has failed to pick up or accelerate within a sufficiently short space of time when a throttle is thrown to wide open position, and this is largely due to the lag of the carbureter mechanism, which permits a too lean mixture to flow to the engine before the various elements have adjusted themselves to the change in conditions.

This invention relates to an auxiliary fuel supply means for a carbureter whereby the sudden draft through the carbureter occasioned by the wide opening of the throttle valve, serves to actuate mechanisms for introducing a charge of fuel to the mixing chamber of the carbureter under pressure and spraying the same in the path of the incoming air.

It is an object of this invention to construct an improved carbureter equipped with a plurality of fuel jets whereby fuel may be introduced into the mixing chamber of the carbureter by aspiration, as well as forcibly sprayed therein under pressure.

It is also an object of this invention to construct an improved carbureter wherein a sudden movement of the inlet air valve thereof serves to force a charge of fuel into the mixing chamber of the carbureter under pressure.

It is also an object of this invention to construct an improved carbureter having an

auxiliary fuel chamber thereon with a piston movable therein and connections between said piston and the valve on the carbureter to force the fuel from said chamber under pressure into the mixing chamber of the carbureter.

It is also an object of this invention to construct a carbureter having an auxiliary fuel nozzle therein adapted to have injected therethrough a charge of fuel under pressure with an initial sudden opening of the throttle valve and continually supplying fuel when the throttle valve is left in wide open position.

It is also an object of this invention to construct a carbureter having a usual inlet needle valve affording communication to the mixing chamber and an auxiliary fuel nozzle adapted to supply fuel in excess of that supplied by the needle valve under heavy loads, and with another nozzle adapted to inject a charge of fuel into the mixing chamber with a sudden opening of the throttle valve or sudden increase of draft of air through the carbureter.

It is also an object of this invention to construct a carbureter having a plurality of auxiliary fuel inlet nozzles each adapted to introduce a charge of fuel into the mixing chamber with a sudden opening of the air inlet valve.

It is also an object of this invention to construct a carbureter having an auxiliary fuel chamber adapted to receive fuel from the float feed chamber of the carbureter and provided with a piston actuatable by the inlet air valve of the carbureter to inject one or more jets of fuel under pressure into the mixing chamber with a sudden opening of the air valve.

It is furthermore an object of this invention to construct a carbureter equipped with a plurality of fuel inlet means to the mixing chamber thereof and with mechanism for introducing a charge of fuel under pressure through certain of said fuel inlet means.

It is finally an object of this invention to construct a carbureter simple in adjustment and capable of rapid variations in the throttle adjustment thereof to insure an immediate responsive action of the motor to which it is connected.

The invention (in a preferred form) is

hereinafter more fully described and defined in the accompanying drawings and specification.

In the drawings:

5 Figure 1 is a front elevation of a carbureter embodying the principles of my invention.

Fig. 2 is a rear elevation thereof.

10 Fig. 3 is a central vertical section taken longitudinally of the carbureter.

Fig. 4 is a horizontal section taken on line 4—4 of Fig. 3.

Fig. 5 is a fragmentary top plan view showing the air inlet valve.

15 Fig. 6 is a section taken on line 6—6 of Fig. 3 with parts omitted.

As shown in the drawings:

The carbureter casing embraces a float feed chamber 1, a mixing chamber 2, an air 20 inlet chamber 3, and a dash pot or pressure cylinder fuel chamber 4. Communication is afforded between the float chamber 1, and the mixing chamber 2, through an offset chamber 5, on one side of the float feed chamber, which communicates with an air passage 6, in communication with the mixing chamber, and on one side thereof. The inlet of fuel to the carbureter from the gasoline supply is through a pipe 7, which is 25 threaded into a plug 8, which is in turn threaded into a plug 9, which is itself threaded into the casing at the lower end of said chamber 5. Said plug 9, is centrally apertured to afford a valve seat for a needle 30 valve 10, which, as shown, is provided with a tubular stem 11, with a peripheral flange 12, thereon. Said plug 9, has a peripheral passage 13, therearound which communicates with the chamber 5, through the upper end of said plug 9, by means of a passage 14. Of course, suitable gaskets are 35 provided between the various threaded members to prevent leakage therethrough.

A spill cup 15, is partially supported in 40 position by said plug 9, due to the clamping of a ring member 16, integral with an extension arm 17, forming a part of said spill cup, said ring 16, being clamped to the lower portion of the casing beneath the 45 chamber 5, by said plug. Said extension 17, is provided with a passage 18, therethrough, which communicates with the peripheral passage 13, in the plug 9, so that fuel in the chambers 1, and 5, may flow downwardly through the passage 14, thence through the passage 13, and into the passage 18, in the spill cup member.

For the purpose of controlling the inlet 50 of fuel to the float feed chamber through said inlet pipe 7, a float 19, is adjustably secured upon a stem 20, the lower end of which is enlarged and rests upon the outer end of a pivoted lever 21, which at its other or inner end, engages beneath said flange 55 12, on the needle valve element 11. Thus, as

the level of fuel within the float feed chamber falls, the float descends and rests upon said lever 21, serving to elevate the needle valve 10, to admit fuel when the level has arisen to a predetermined amount, when the weight of the float is removed from the lever 21, a spiral spring 22, coiled around said tubular element 11, of the needle valve, impels the same downwardly again into closed position. An axially apertured guide element 23, is threaded into a partition 24, separating the chambers 5, and 6, thus affording a guide for said needle valve element, the portion 11, of which surrounds the same, and also provides communication between the respective chambers.

A spring thrust needle valve 25, is mounted in said chamber 6, and is normally impelled downwardly by a spring 25^a to close the aperture in said element 23. Connected 55 air inlet valves and outlet valves are provided in the mixing chamber and are respectively denoted by the reference numerals 26, and 27, with a connecting rod 28, pivotally connected to each of said butterfly valves, serving to insure simultaneous operation thereof. The valve 27, which is termed the throttle valve of the carbureter is keyed upon a shaft 29, which has secured at a point on the outer side of the casing 95 an actuating throttle lever 30. Mechanism is provided for insuring a proportionate opening of the needle valve 25, with the aforesaid valves 26, and 27, but inasmuch as this forms no part of this invention a 100 brief description thereof will suffice.

An adjustable cam element 31, is secured on the outer end of said shaft 29, adjacent the lever 30, and bears against the extremity of an arm 32, of a bell crank, which is 105 pivotally mounted on a transverse shaft 33, on the carbureter. A hollow tubular bracket 34, is provided with an extended lug 35, which is keyed upon said shaft 33, so that actuation of said tubular member 110 34, will cause rotation of said shaft 33. In order to rotate said tubular member 34, coincidently with movement of the throttle valve lever 30, the other arm 36, of said bell crank is provided with a set screw 37, 115 which bears against a cam 38, on the extremity of a shaft 39, extending through said tubular element. Accordingly, when the lever 30, is actuated the cam 31, will depress the arm 32, of the bell crank, thus 120 causing the other arm 36, thereof through the intermediation of the set screw 37, to thrust said cam element 38, to one side with a consequent pivotal movement of the tubular element 34, and a rotation of said shaft 33. Said shaft 33, at its inner end is provided with an arm 40, which engages in a notch in the needle valve element 25, to raise and lower the same with even a slight movement of said transverse shaft 33.

The upper end of said shaft 39, is provided with an arm 42, to which is connected a rod or cable 43, for manual actuation whereby the needle valve may be opened 5 without opening the throttle valve in order to admit an over-abundance of fuel thereto when starting the engine. When the rod or cable 43, is pulled by the operator, the shaft 39, is rotated, in the tubular element 34, thus 10 causing a corresponding movement of the cam 38, on the lower end thereof, which, bearing against the end of the set screw 37, causes the tubular element to be slightly rotated with a consequent rotation of said 15 shaft 33, and opening of the needle valve 25.

A reducing plug or coupling 44, is threaded into the lower end of the float feed chamber and secured therein is one end of a pipe 45, which at its other end communicates in 20 said dash pot or piston chamber 4. Slidably mounted in said chamber is a piston 46, connected on a piston rod 47, which extends upwardly into the air inlet chamber 3, and is there rigidly secured to a puppet 25 valve 48. A spiral spring bears at one of its ends against said puppet valve 48, and at its other upon the partition between the respective chambers 3 and 4, thus normally impelling said puppet valve into 30 closed position with the piston in raised position in the dash pot cylinder 4.

The pipe 45, opens into chamber 4, above the piston 46, which at all times prevents a vacuum from being formed above the piston 17, and also as the rate of passage of 35 the fluid through passage 45, is limited, a cushioning effect is provided which prevents the air valve from snapping shut and clattering.

40 The closure element for said valve 48, is adjustable to and from the valve in order to vary the spring pressure on the latter as desired. For this purpose said closure 49, is in threaded engagement with the upper 45 walls of the chamber 3, and is provided with a series of flutes or notches 50, on the outer periphery thereof adapted to be engaged by the spring pressed detent 51, to maintain the same in adjusted position.

50 Said spill cup 15, is provided with an apertured lug 52, in the bottom thereof into which is threaded a fuel nozzle 53, which projects upwardly into the mixing chamber of the carburetor, through a slot in the 55 air butterfly inlet valve 26. A hollow plug 54, having a peripheral passage 55, communicating with said hollow interior by suitable apertures, is threaded into the under face of said cup 15, in alinement with the 60 nozzle 53, and by such threaded engagement serves to clamp therein a ring element 56, of a pipe 57, which is provided with another ring element 58, engaging around a peripheral passage 59, in a hollow plug 60, 65 threaded into the bottom wall of said cham-

ber 4. Also communicating in said ring element 58, is a pipe 61, which leads upwardly and through the air passage 3, and is there directed upwardly into the mixing chamber of the carburetor at a point above 70 said nozzle 53. Thus it is apparent that fuel may flow to the nozzle 53, from the float feed chamber through the various passages leading to the passage 18, and also from the chamber 4, to said nozzle through 75 the various passages leading to the pipe 57. Fuel may also be admitted to the mixing chamber through the pipe 61, which leads directly from the ring element 58, wherein it is in communication with the hollow interior of the plug 60. An air inlet port 62, is provided in the side walls of the chamber 6, to admit a flow of air at all times when the throttle valve is slightly open, across the inlet of the fuel needle valve 25. Connected annular passages 63, are cast upon the casing surrounding the mixing chamber for the purpose of water jacketing the same if desired, and tubular connections 64 and 65, respectively, are provided for the purpose of attaching the inlet and outlet water pipes thereto.

The operation is as follows:

A certain quantity of fuel is maintained in the float feed chamber at all times by 95 the automatic action of the float, which serves to admit fuel thereto from time to time. When the throttle valve 27, is opened of course the needle valve 25, is raised from its seat, thus permitting a flow of fuel 100 therethrough to be mixed with air entering at the port 62, and likewise through the inlet air valve 26, the mixture then passing to the manifold of the engine.

This carburetor is particularly adapted 105 to supply a proper and sufficient amount of fuel to the engine with a sudden opening of the throttle valve to enable the engine to instantly accelerate or pick up. For this purpose an auxiliary puppet air inlet valve 110 48, is provided, the valve stem of which is connected to the piston 46, in the dash pot chamber 4, so that as the air inlet valve is suddenly opened, due to an excessive draft exerted by the engine as when the throttle 115 valve is thrown wide open, the piston is forced downwardly, thus pressing on the fuel in the chamber and causing the same to spurt upwardly under pressure through said pipe 61, which of course injects the 120 fuel into the mixing chamber of the carburetor. The fuel underpressure is also forced through the pipe 57, and thence upwardly through the nozzle 53, so that a plurality of jets of hydrocarbon are introduced into the mixing chamber under pressure. The amount of fuel so forced through the nozzle 53 is considerably less than that forced through the pipe 61, owing to the 125 smaller diameter of the orifice in the former. 130

If the throttle valve is left open, of course the initial pressure in the dash pot chamber is dissipated with a cessation of movement of the piston, but the intense draft of the engine will serve to continue the flow of hydro-carbon through the spray nozzle 53, which receives the supply from the passage 18, connected to the float feed chamber as described, and a certain amount will also be drawn up through the pipe 61, which receives its supply from the chamber 4. The piston 46, not only serves to inject a charge of fuel into the mixing chamber with movement thereof but also has a dampening effect upon the auxiliary air inlet valve 48, to prevent fluttering of the same.

I am aware that various details of construction may be varied through a wide range without departing from the principles of this invention. I therefore do not purpose limiting the patent granted otherwise than necessitated by the prior art.

I claim as my invention:

1. In a device of the class described a carbureter comprising a float feed chamber, a mixing chamber, an air inlet chamber, a dash pot chamber, a pipe connecting said float feed chamber and said dash pot chamber to admit a flow of fuel to the latter, a spray nozzle projecting into the mixing chamber, unrestricted passages connecting said spray nozzle with said float feed chamber, a passage connecting said spray nozzle with said dash pot chamber, an air valve for said air chamber, and a piston adapted to be actuated thereby in said dash pot chamber to force a charge of fuel through said spray nozzle into the mixing chamber of the carbureter.

40 2. In a device of the class described a carbureter comprising a float feed chamber, a mixing chamber, an air inlet chamber, a dash pot chamber, an air inlet valve in said air inlet chamber, a piston in said dash pot connected to said air inlet valve, communication between said float feed chamber and said dash pot chamber to admit a flow of fuel to the latter, a spray nozzle projecting into the mixing chamber, and communicating with said float feed chamber, a passage connecting said spray nozzle with said dash pot chamber, and a second spray nozzle communicating with said passage, between said first spray nozzle and said dash pot chamber thus permitting a plurality of jets of fuel to be injected into the mixing chamber when said piston is actuated in the dash pot chamber.

60 3. In a device of the class described a float feed chamber, a mixing chamber, a dash pot chamber, a piston in the dash pot chamber, spray nozzles projecting into the mixing chamber and each thereof having connections with said dash pot chamber and with 65 said float chamber, another connection be-

tween the float chamber and said dash pot chamber, and means adapted to actuate said piston to force a charge of fuel under pressure into the mixing chamber of the device through said spray nozzles.

70 4. In a device of the class described a carbureter comprising a float feed chamber and a mixing chamber, an auxiliary fuel chamber, a piston movable therein, spray nozzles projecting into the mixing chamber, one at a greater height than the other, a series of passages connecting said float feed chamber and said auxiliary fuel chamber, said spray nozzles connected in the line of communication of said passages, and a pipe 75 connecting said float feed chamber and said auxiliary chamber independently of said passages.

75 5. In a device of the class described a piston rod, a valve at one end thereof, a piston at the other end thereof, a spring between said valve and piston adapted to hold the same in normal position, and a plurality of hydrocarbon nozzles through which jets are introduced at different levels 80 into the mixing chamber of a carbureter by said valve and piston when a sudden draft of air takes place through the carbureter.

85 6. In a device of the class described a carbureter, a spring pressed auxiliary air valve 90 thereon, a piston connected to simultaneously move therewith, a fuel chamber inclosing said piston, and a plurality of spray nozzles communicating with said chamber to admit a charge of fuel therethrough into 95 the mixing chamber of the carbureter at different levels when said piston is actuated by movement of said air valve.

100 7. In a device of the class described, a float feed chamber, a carbureting chamber, an air inlet thereto, a spring resisted valve for said inlet, a fuel spray nozzle adapted to direct fuel into said carbureting chamber, a dash pot forming a part of said carbureter, a piston in said dash pot connected for 105 movement with said air inlet valve so that downward movements of said valve impart a downward movement to said piston in said dash pot, a passage communicating between said float feed chamber and the upper portion of said dash pot behind said piston, and a passage communicating between said fuel spray nozzle and said dash pot in front of said piston whereby movement of said piston by the air valve forces a charge of 110 fuel into the carbureting chamber through said spray nozzle.

115 8. In a carbureter of the class described, a float feed chamber, a carbureting chamber, a nozzle for fuel projecting into said carbureting chamber, an air port in said carbureter for admitting air past said nozzle, an auxiliary air port in said carbureter, a spring resisted valve in said auxiliary air port, a dash pot formed on said carbureter, 120

a piston in said dash pot operatively connected to said auxiliary air valve to receive movement therefrom, a passage communicating between said float feed chamber and 5 said dash pot to convey fuel into the dash pot on one side of the piston therein, and a passage communicating between said fuel nozzle and said dash pot, said passage communicating into said dash pot on the other 10 side of said piston whereby movements of said piston imparted thereto by movements of the air valve force a charge of fuel under pressure through said nozzle in excess of that which is withdrawn due to the aspiration 15 effect of air passing said nozzle.

9. In a carbureter of the class described, a float feed chamber, a nozzle to supply a fuel into the carbureter for carburetion of air admitted therethrough, a dash pot forming a part of said carbureter, a piston in 20 said dash pot, a suction operated air valve in said carbureter, a connection between said air valve and said piston to impart motion to the piston when the air valve is actuated, a 25 passage communicating with said float feed chamber and said dash pot, and another passage communicating with said dash pot and said fuel supply nozzle, the openings of said respective passages into said dash pot 30 being so situated with reference to said piston that an opening movement of said air valve operates the piston to withdraw fuel from the float feed chamber and discharge fuel under pressure from the dash pot into 35 said nozzle independent of and in excess of the aspiration effect of the air passing said nozzle.

10. In a carbureter of the class described, a float feed chamber, a carbureting chamber, 40 an inlet chamber for air, a dash pot chamber, a passage communicating with said float feed chamber and said dash pot chamber to admit fuel from the float feed chamber to the dash pot chamber, a spray nozzle projecting 45 into the carbureting chamber, means affording communication between said spray nozzle, said float feed chamber and said dash pot chamber, an air valve for said air inlet chamber, a piston mounted in said dash pot 50 adapted when actuated to force a charge of fuel through said spray nozzle into the carbureting chamber, and a stem on which said air valve and piston are mounted whereby said piston is moved in the dash pot due to 55 a suction effect on said air valve whereby the same is moved.

11. In a carbureter of the class described, a float feed chamber, a carbureting chamber, an air passage leading to said carbureting 60 chamber, a fuel spray nozzle situated to discharge into the carbureting chamber and subjected to the aspiration effects of the air flowing through said air passage into said carbureting chamber, an auxiliary air inlet, 65 a suction operated valve in said air inlet,

a dash pot forming a part of said carbureter, a piston in said dash pot operatively connected to said suction operated air valve so as to be actuated by said valve, a passage affording communication between said float 70 feed chamber and said dash pot, a passage affording communication between said float feed chamber, said dash pot and said fuel spray nozzle, a throttle valve to control the flow of mixture from the carbureting chamber, and a valve controlling the flow of air through said air passage leading to the carbureting chamber. 75

12. In a carbureter of the class described, a float feed chamber, a carbureting chamber, 80 an air passage leading to said carbureting chamber, a fuel spray nozzle situated to discharge fuel into the carbureting chamber and subjected to the aspiration effect of air flowing through said air passage to 85 said carbureting chamber, an auxiliary air inlet, a suction operated valve in said air inlet, a spring resisting movement thereof, a dash pot forming a part of said carbureter, a piston in said dash pot, a stem connected 90 to said piston and to said air inlet valve to insure coincident operation of said piston with said air valve, a passage affording communication between said float feed chamber and said dash pot on one side of said piston, 95 and a passage affording communication between said fuel spray nozzle and said dash pot on the other side of said piston to permit a charge of fuel to be forced through said nozzle into the carbureting chamber independent of and in excess of the aspiration effect of the air upon said fuel nozzle when the suction operated valve is operated to thrust said piston downwardly in said dash pot. 100

13. In a carbureter of the class described, a float feed chamber, a carbureting chamber, a dash pot forming a part of said carbureter having a piston therein, an unrestricted fuel nozzle projecting into said carbureting chamber, a port for supplying air into said carbureting chamber to utilize an aspiration effect on said fuel nozzle, an auxiliary air port, a valve in said auxiliary air port, connections between said valve and said piston whereby said piston is operated when said valve is actuated by suction through the carbureter, means supplying fuel from the float feed chamber to said dash pot, and communications between said fuel nozzle and said dash pot whereby said fuel may be forced through said nozzle into said carbureting chamber with actuation of the auxiliary air valve. 110

14. In a carbureter of the class described, 115 a carbureting chamber, a fuel supply nozzle to direct fuel thereto, an air inlet passage to admit air into said carbureting chamber past said fuel nozzle, a butterfly valve controlling the flow of air through said passage, 120 130

- an auxiliary air inlet passage to admit air into the carbureting chamber; a dash pot associated with said carbureter, a piston therein, means admitting fuel to said dash pot chamber, a communication between said dash pot chamber and said fuel supply nozzle whereby movement of the piston forces fuel under pressure into said carbureting chamber, and an air valve mounted in said auxiliary air inlet passage and operatively connected to the piston in the dash pot to operate the same when said auxiliary air valve is operated by suction in the carbureter.
15. In a carbureter, the combination of a mixing chamber, a main fuel nozzle, float feed means for supplying fuel to the main fuel nozzle, a pump operated by sudden increase in suction in the carbureter to provide an extra supply of fuel, the said pump being provided with a plurality of ducts having outlets in the mixing chamber at different elevations so as to operate differentially in supplying fuel to the mixing chamber.
16. In a carbureter, the combination of a mixing chamber, a main fuel nozzle, a float feed chamber for supplying fuel to the main fuel nozzle, a pump operated by sudden increase of suction in the carbureter to provide an extra supply of fuel, a passageway connecting the pump and float feed chamber, an auxiliary nozzle communicating with said passageway, and an auxiliary nozzle communicating directly with the pump.
17. In a carbureter, the combination of a mixing chamber, a main fuel nozzle, a float feed chamber for supplying fuel to the main fuel nozzle, an air inlet valve, a pump operated by the air inlet valve to provide an extra supply of fuel to the mixing chamber when the valve is suddenly opened, a fuel passageway connecting the pump and the

float feed chamber, and a fuel nozzle in the mixing chamber communicating with said passageway intermediate of the pump and the float feed chamber.

18. In a carbureter, the combination of a mixing chamber having a main fuel nozzle, an air inlet adjacent the main fuel nozzle, a plurality of auxiliary air passageways, a pump for increasing the normal supply of fuel, and an auxiliary fuel nozzle supplied with fuel by said pump and located at the intersection of the said auxiliary air passageways.

19. In a carbureter, the combination of a mixing chamber having a main fuel nozzle, a main fuel reservoir, float feed means for furnishing a normal supply of fuel to the main fuel nozzle, a pump piston for augmenting the normal supply of fuel, and a chamber inclosing the pump piston, said chamber being provided with a passageway therefrom at each side of the piston communicating with the main fuel reservoir.

20. In a carbureter, the combination of a mixing chamber, a main fuel nozzle in the mixing chamber, a main fuel reservoir, float feed means for providing a normal supply of fuel to the main fuel nozzle, a pump piston, a chamber inclosing the said pump piston, and having a passageway therefrom at each side of the piston communicating with the main fuel reservoir, and an auxiliary fuel nozzle communicating with one of said passageways for supplying fuel to the mixing chamber by aspiration and by pressure.

In testimony whereof I have hereunto subscribed my name in the presence of two subscribing witnesses.

WILLIAM A. EDWARDS.
